BRUSH AND AN APPLIANCE FOR USING
THE SAME

William H. Scott, Rochester, N. Y.

Application May 29, 1936, Serial No. 82,607

3 Claims. (Cl. 15—127)

This invention relates to a brush and an appliance for using the same.

One object of the present invention is to provide a brush for communicating connection with a spigot or faucet or other source of water supply for massaging and shampooing purposes or for cleaning sinks, cooking utensils or dishes and for various other uses and possessing sufficient elasticity or flexibility under hand pressure to insure effective operations in the use of the brush head.

Another object of the invention resides in the provision of a brush of the nature stated, embodying among other characteristics, simplicity, durability, sanitation, economy in the matter of production and effectiveness in operation.

A still further object of the invention is to provide an appliance including a brush adapted for connection with a suitable source of water supply in combination with means for instrumentalities arranged to introduce regulated quantities of a cleaning or cleansing agent into the appliance for passage with the water through the brush head.

With these and other objects in view, the invention consists in the construction and novel combination and arrangement of parts herein-after fully described, illustrated in the accompanying drawing and pointed out in the claims hereto appended, it being understood that various changes in the form, proportion and minor details of construction, within the scope of the claims, may be resorted to without departing from the spirit or sacrificing any of the advantages of the invention.

In the drawing:

Fig. 1 is a view partly in elevation and partly in section illustrating one adaptation of the invention.

Fig. 2 is a vertical sectional view on the line 2—2 of Fig. 1.

Fig. 3 is a similar view on the line 3—3 of Fig. 2.

Fig. 4 is a horizontal sectional view on the line 4—4 of Fig. 1.

Fig. 5 is a detail view of the cleansing medium container controlling valve.

Fig. 6 is a bottom plan view of the brush.

Referring now more particularly to the accompanying drawing, the reference character A indicates, generally, a brush composed of a single piece of rubber or other suitable yieldable or flexible material having an upper relatively thick portion 1 for body strength, and having a substantially conical or other shaped interior chamber 2, formed by a bottom wall 3 and side walls

4 which converge from the bottom wall to an inlet orifice 5.

The bottom wall 3 of the brush has outwardly extending, exteriorly tapered, spaced, flexible massaging fingers 6. Each finger is provided at its inner end with an inverted substantially conical shaped or other form of tapering cavity 7. The major or larger end of each cavity is arranged at the inner face of the bottom wall 3 with the minor or smaller end of the cavity communicating with a duct 8 leading to and through the outer end of the respective finger 6.

By virtue of the single piece of material of which the brush is formed, it is maintained in a sanitary condition, having no creases or parts where soap or foreign matter might lodge and can be easily and readily cleaned. The single piece formation has the additional advantage in that it obviates possibility of accidental separation of parts due to heavy or varying pressures of water passing through the brush in the use of the same. The provision of the cavities 7 prevents backwash or formation of eddies which latter would tend to retard the flow of liquid from the chamber 2 through the fingers 6.

The brush is of relatively small size in order that it may be readily held in the operator's hand by the latter's fingertips when using the brush for rubbing, scrubbing or massaging or cleansing purposes, and to facilitate an effective grip of the brush by the fingertips and to also facilitate yielding action of the brush in the use of the same under pressure of the operator's hand.

To provide for an easy and effective grip of the brush in the operator's hand, I provide an annular or continuous groove 9 in the exterior surface thereof opposite the chamber 2, and to prevent the user's finger nails possibly contacting with a patient's scalp or body to the injury of the patient, I provide a flexible guard in the nature of an annular or continuous laterally and upwardly extending rib 10 adjacent the lower portion of the groove 9.

By virtue of the recesses 11 formed incident to the tapering formation of the fingers 6 together with the thin bottom 3 and the cavities 7, and the thinness of the body portion at the groove 9, as compared with the thicker upper portion of the brush, adjacent the inlet orifice 5, the brush is readily compressed slightly incident to its yieldable or flexible nature and the fingers, due particularly to their taper and to the thinness of the bottom 3, are readily flexed horizontally and also readily flexed inwardly and outwardly with relation to the chamber 2. The

brush has yieldability and yet it is effectively stable or possesses sufficient rigidity to provide for an effective rubbing or massaging operation.

The thickness of the inner portion of the brush 5 at the inlet orifice 5 provides for an effective mounting of the inner end 12 of a tubular nipple B which is provided with one or more ribs 13 designed to coact with the flange 14 on the nipple B to provide for an effective, tight mounting 10 of the nipple B in the body portion of the brush. The flange 14 is designed to fit tightly upon the flat surface 15 of the body portion and thereby coact with the rib 13 to prevent accidental dislodgment of the nipple B from its seat in the orifice 5.

A flexible or other tubing 16 has one end removably slipped over the outer end 17 of the nipple B, there being a rib 18 formed on the portion 17 of the nipple B to bite or press into the 20 inner surface of the tubing 16 to form a tight connection between the tubing 16 and the nipple B and yet effect a removable connection thereat. This flexible tubing 16 is designed to have its opposite end connected directly to the outlet 19 25 of a common or other suitable spigot C to provide for the introduction of water under pressure for passage through the tubing 16 and to and through the brush A in a manner which will be readily understood.

30 In one embodiment of the present invention, the rubber or other tubing 16 is connected at one end to a hollow nipple 20 which depends from the bottom 21 of a soap or other liquid cleansing material container D. The hollow nipple 20 is 35 provided with grooves to form intervening ribs in a common manner to provide for an effective, tight, but detachable connection of the tubing with the nipple, as will be readily understood.

The container D is provided with a bottom 40 formed of downwardly converging walls 22, spaced from the bottom 21 and designed to feed, by gravity, the liquid cleansing substance in the container to an orifice 23 in the wall 23' in the bottom of the container D for the passage of the liquid into a slightly tapered valve casing 24 45 formed in the bottom of the container.

A tapered valve 25 is mounted in the valve casing 24 and this valve may be of any suitable type but it is preferably tapered slightly to conform 50 with the taper of the valve casing 24. It is provided with an annular groove 26 to receive the inner end of a removable screw or other suitable element 27 to maintain the valve 25 in its seat in the valve casing against accidental dislodgment and upon removal from its screw threaded 55 socket 27' permit removal of the valve 25 from its seat or casing.

The valve 25 also has a transverse perforation 29 adapted to be brought into registration 60 with the orifice 23 in the wall 23' of the container and with the orifice 23a in the bottom of the valve casing 24 to permit flow of the cleansing medium from the container D through the valve and its casing to and through the tubing 65 16 to the brush. For instance, when the handle 30 is in the full line position, the liquid cleansing medium is cut off from discharge from the container D because the aperture 29 in the valve 25 is at right angles to the orifice 23 and the nipple 20, permitting flow of water past the valve and the casing by way of the passage 28 (see Fig. 3). When the lever or handle 30 is turned to the dotted line position in Figure 1, the aperture 29 is aligned with said orifices 70 23 and 23a to permit flow of the liquid cleans-

ing medium in regulated quantities through the aperture 29 into the tubing 16. The aperture 29 may align completely with the orifices 23 and 23a or only partially register with the same in order to further regulate the flow of liquid cleansing medium to the tubing 16. The liquid cleansing medium becomes mixed with the water under pressure flowing through the passage 28 from the spigot C and by the water under pressure is delivered through the flexible tubing 16 to the chamber 2 of the brush, under pressure, and forced from the chamber 2 under pressure through the hollow fingers 6 for shampooing of hair or for massaging and cleansing the body of a patient.

To provide for the supply of water under pressure, and to mount the container D adjacent a spigot or faucet, I secure to or form with the container D the curved hollow arm 31, the passage 28 of which opens at its inner end into the aforesaid hollow nipple 20 below the valve casing 24 for the passage of the water under pressure from the spigot or faucet C to the flexible tubing 16 for delivery to and passage of the water under pressure to and through the brush, as should now be well understood.

The outer end of the hollow arm 31 is provided with a turnable coupling nut 32 which is held turnably on the curved hollow arm 31 by a common type of flanged nipple 33, as shown, pressed or otherwise secured in the arm 31. This coupling member 32 is interiorly screw threaded for working screw threaded fit with the exteriorly screw threaded end 33 at the end of the outlet 19 of the spigot or faucet. Thus, the container D is rigidly supported from and adjacent to the spigot or faucet by connection with the latter, and it will be understood that the valve of the spigot or faucet may be readily operated by the valve knob 34 to open and close the valve and when opened to provide for regulated flow and consequent regulated pressure of water from the source of water supply to the container and therefrom to the brush.

For the sake of attractiveness, the container 45 D is made ornamental, and the cover 34 thereof may be secured on the container in any suitable well known manner, preferably by a bayonet-slot connection formed by the provision of a slot a formed part way into the outer surface of the container at the top thereof to receive a slightly inwardly directed projection b formed by punching or otherwise extended from the inner surface of the flange c of the cover 34. The container and its cover are formed preferably of aluminum 55 or other suitable material.

A vent pipe 35 is mounted in the container D at its upper end and is adapted to project above the level of the liquid soap or other cleansing medium. The vent pipe 35 is connected with the tubing 16 by way of orifices 29' and 29a in the valve 25 when supplying cleansing medium for admixture with the water. There is a certain amount of vacuum created and the vent pipe allows the vacuum to escape.

The brush being formed of a single piece of rubber or similar flexible or yieldable material, the use of separate parts or the use of metallic or other clamping devices are obviated, and by virtue of the flexible bottom of the brush chamber the water or fluid in the brush chamber may be compressed therein either by inward or outward movement of the fluid discharge fingers by varying hand pressures on the brush during treatments of the scalp or body or by an inward flexing of

the side walls of the chamber or both and incident to the compression of the fluid in the brush chamber control or regulate the degree of force of flow of discharge of the fluid through the nozzles or fingers 6, the rib 10 effectively serving to keep the operator's finger nails away from possible injurious contact with the patient's scalp or body during use of the brush.

What is claimed is:

- 10 1. In an appliance of the class described, a brush including a body portion having an interior chamber and provided at the bottom wall thereof with outwardly extending massaging fingers having ducts communicating with the interior chamber, said body being also provided with a continuous rib extending outwardly and upwardly from the body and arranged to receive the finger tips and prevent the same from slipping out of contact with it and coming in contact with a person when the brush is used for massaging.
- 15 2. In an appliance of the class described, a brush including a body portion having an interior chamber and provided at the bottom thereof with massaging fingers having ducts communicating with the interior chamber, said body

portion being provided with an exterior continuous groove extending entirely around the body and arranged to receive the tips of the fingers, and a continuous rib extending upwardly and outwardly from the body of the bottom of the groove and arranged to prevent the finger tips from slipping off the body when the brush is in use. 5

3. In an appliance of the class described, a brush including a body portion having an interior chamber and provided at the bottom with massaging means having ducts communicating with the body, said body being provided above the massaging means with a continuous groove arranged to receive the finger tips and presenting a substantially concave surface to the same and a continuous rib extending upwardly and outwardly from the body at the bottom of the groove and having its inner face forming a continuation 10 of and merging into the surface of the groove and arranged to prevent the finger tips from slipping out of the groove when the brush is in use. 15
